Max Wenzel

By W. F. Davis & Son
Attorney

UNITED STATES PATENT OFFICE.

MAX WENZEL, OF KANSAS CITY, MISSOURI.

CLOTHES-TONGS.

1,386,295.

Specification of Letters Patent. Patented Aug. 2, 1921.

Application filed October 6, 1917. Serial No. 195,121.

To all whom it may concern:

Be it known that I, MAX WENZEL, a citizen of the United States, residing at Kansas City, in the county of Jackson and State of Missouri, have invented certain new and useful Improvements in Clothes-Tongs, of which the following is a full, clear, and exact description, such as will enable others skilled in the art to which it appertains to make and use the same.

The invention relates to clothes tongs and seeks to provide a simple and efficient form of tongs for handling clothing in water and the like.

During the process of washing and rinsing clothing it is necessary to handle the clothing considerably both in and out of the water and a suitable tongs will prevent soiling the clothing with the hands and also prevent soiling the hands with the water which becomes soiled from the soiled clothing. The tongs will also prevent scalding the hands when the water is at or near the boiling point.

The present invention seeks to provide an improved tongs for handling wash clothing and the like.

With these and other objects in view the invention consists in the features of construction, combinations and arrangements of parts hereinafter set forth and more particularly pointed out in the appended claim, the accompanying drawing illustrating a form of the improved clothes tongs.

In the drawings:

Figure 1, is a view in full lines of the tongs in open position and showing in dotted lines the position when closed.

Fig. 2 is an enlarged fragmentary broken view showing the form of hinge.

Fig. 3, is a cross section taken on line 1-1 of Fig. 1.

Fig. 4 is a fragmentary view of one of the legs of the tongs, the legs being duplicate so far as shown by this view.

Fig. 5, is a fragmentary sectional view taken on line 4-4 of Fig. 4.

The legs 6 are duplicate excepting for the notch 7 in one leg and the corresponding lug 8 in the opposite leg, each leg being provided with the cavity 9 in which the connecting plate 10 is loosely fitted, the pins 11 passing through the legs 6 and the plate 10 and forming the connecting hinge for the legs so that they can be opened to the

position shown in full lines of Fig. 1 and closed to the position shown in dotted lines of the same figure.

The plate 10 is provided with the slotted holes 12 in which the pins 13 play freely 60 to and fro as the tongs are opened or closed, the pins being rigid in the legs 6.

The pin or shaft 14 is loosely fitted in the holes 15 of the legs 6 and has loosely mounted thereon, the coiled compression spring 65 16, the spring being of sufficient length and stiffness to retain the legs normally in open position as shown, and the holes 15 being counterbored at 17 so that the spring will compress within the legs and allow the tongs 70 to be closed to the position of the dotted lines of Fig. 1.

The lug 8 fits into the notch 7 when the tongs are closed and forms a grip to prevent the clothing from slipping from between the legs of the tongs when very thin articles of clothing are gripped, the notch and lug forming an uneven surface to prevent slipping of heavy articles or bundles of clothing.

The tongs are held in the hand at a point between the pins 11 and the opening and closing ends of the legs 6, and a light pressure of the operator's hand will not prevent the spring 16 from holding the legs in open position, while a firm grip of the hand will close the tongs upon the clothing, so that the latter can be lifted from the water or other location from which it is desired to remove the clothing.

What I claim as new and desire to secure by Letters Patent, is:—

In clothes tongs, a pair of legs of duplicate form excepting the gripping end thereof, the inner face of each of said legs forming an obtuse angle longitudinally of the leg, the vertex of the angle of each of said legs facing the vertex of the angle of the opposing leg and in close proximity thereto, a cavity in the inner side of each of said legs at the vertex of the angle and reaching longitudinally in both directions therefrom, a plate in said cavities, a pin in each of said legs near the vertex of the correspondng angle and through said plate and hingedly 95 connecting said legs so that when said tongs are closed the side of the angle reaching from the vertex to the gripping end of each of said legs is lying against the correspondng side of the opposing leg and when said 100 105 110

tongs are open the side of the angle of each leg reaching from the vertex to the opposite end of the tongs is lying against the corresponding side of the opposing leg, a hole with a closed end in each of said legs between the vertex of the angle thereof and the gripping end of the tongs, said holes

each counterbored, a pin in said holes, a compression spring on said pin and in the counterbores, the tension of said spring tending to hold the gripping end of said tongs open, and means on the gripping end of the tongs to hold clothes.

MAX WENZEL.
